[57]**CLAIM**

The ornamental design for a vegetation scalping and earth boring tool as shown.

DESCRIPTION

FIG. 1 is a downward perspective view of the vegetation scalping and earth boring tool showing my new design;

FIG. 2 is a fragmentary side elevational view thereof taken along line 2—2 of FIG. 1, the remaining side being identical to the side shown; and

FIG. 3 is a bottom plan view of FIG. 1.
